(57) **CLAIM**

I claim the ornamental design for a dust cap for fiber optic adapters, as shown and described.

DESCRIPTION

FIG. 1 is a perspective view of a dust cap for fiber optic adapters;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a center section view taken from FIG. 4 thereof; and,

FIG. 9 is a center section view taken from FIG. 6 thereof. The broken lines shown represent portions of the dust cap for fiber optic adapters that form no part of the claimed design.
